(57) **CLAIM**

The ornamental design for a unity heart assembly, as shown and described.

DESCRIPTION

FIG. 1 is a perspective view of a unity heart assembly constructed in accordance with the present invention;

FIG. 2 is a top view of the unity heart assembly as shown in FIG. 1;

FIG. 3 is a front view of the unity heart assembly as shown in FIG. 1;

FIG. 4 is a back view of the unity heart assembly as shown in FIG. 1;

FIG. 5 is a bottom view of the unity heart assembly as shown in FIG. 1 (the area in dashed line is disclaimed);

FIG. 6 is a left side view of the unity heart assembly as shown in FIG. 1; and,

FIG. 7 is a right side view of the unity heart assembly as shown in FIG. 1.
